FIG. 6

INVENTOR
CLARENCE E. PARKER

By Paul, Paul & Moore
ATTORNEYS

UNITED STATES PATENT OFFICE.

CLARENCE E. PARKER, OF MINNEAPOLIS, MINNESOTA.

EXCAVATING MACHINE.

Application filed August 9, 1922. Serial No. 580,680.

To all whom it may concern:

Be it known that I, CLARENCE E. PARKER, a citizen of the United States, resident of Minneapolis, county of Hennepin and State 5 of Minnesota, have invented certain new and useful Improvements in Excavating Machines, of which the following is a specification.

This invention relates to, and has for its 10 object the provision of new and useful improvements in excavating machines particularly of the type employed in digging open ditches and trenches for tiling, etc.

A more specific object is to provide an 15 improved dipper mechanism and also to dispense with the heavy dipper arm usually necessary for supporting the dipper on machines of this type.

A further object is to provide an improved boom having a longitudinal track on 20 which the dipper carriage may travel when the dipper is being loaded or unloaded.

A further object is to provide a simple 25 and efficient means for tripping and releasing the loaded dipper for depositing the excavated material on either side of the ditch or trench.

A still further object is to provide a dipper 30 capable of digging very deep and narrow ditches or trenches.

Other objects of the invention will more 35 fully appear from the following detailed description and the accompanying drawings and will be pointed out in the annexed claims.

In the accompanying drawings there has 40 been disclosed a structure designed to carry out the objects of the invention, but it is to be understood that the invention is not confined to the exact features shown, and various changes may be made within the scope of the claims which follow.

In the drawings:

Figure 1 is a side elevation of an excavating machine embodying my invention 45 and showing the dipper in position to be loaded;

Figure 2 is a detail view showing the dipper being filled;

Figure 3 is a detail view showing the dipper in its loaded raised position and also showing the dipper-supporting carriage and the means for tripping and releasing the dipper;

Figure 4 is a view similar to Figure 3

but showing the dipper in its unloading position;

Figure 5 is a plan view of the parts shown in Figure 3;

Figure 6 is a transverse sectional view on 60 the line 6—6 of Figure 5;

Figure 7 is a transverse sectional view on 65 the line 7—7 of Figure 5 showing the rear end of the dipper.

In the selected embodiment of the invention here shown for the purpose of disclosure, there is illustrated an excavating machine 11 comprising a motor 12, loading drum 13 and lifting and unloading drum 14, mounted on a frame 15, which is supported 70 on a turn-table 16 mounted on the usual truck or caterpillar 17. To the rear end of the frame 15 a mast 18 is pivotally mounted at 19 and extends rearwardly in an inclined position. A supporting member 21 has one 75 end pivotally connected to the mast at 22. A cable 23 is secured to the forward end of this member 21 and extends forwardly passing through a tackle block 24 secured to an upright frame 25, thence rearwardly 80 through a similar tackle block 26 and again forwardly to a winding drum 27 rotatably mounted in bearing secured to the frame 25. This drum may be operated by any suitable means and I have here shown it as driven by 85 a chain 28 from the drum 14. The means for controlling the drum may be of any well known type and construction suitable for the purpose and it is therefore unnecessary to show the same in detail. The above- 90 described mechanism functions when raising and lowering the mast. A boom 29 is pivotally connected at 31 to the lower and forward end of the mast 18 and adjacent to the pivot 19. This boom preferably consists of 95 upper angle bars 32 and lower T-bars 33 united by diagonal braces 34 riveted thereto, as shown in Figures 3, 4 and 5, thus providing a very light and rigid frame construction of substantially rectangular cross 100 section, as shown in Figures 6 and 7. As will be noted in these same figures the outer flanges of the T-bars 33 are arranged in such a manner as to provide a longitudinal track 35, on which the dipper-supporting carriage 105 may travel.

This carriage preferably consists of a pair of side-bars 36, joined together at their forward ends by a cross member 37 here shown as being integral with the bars. A 110

pair of lugs 38 are preferably provided on the cross member and project forwardly therefrom to support a rod 39 on which is mounted a pair of hangers 41 having anti-friction rollers 42 arranged to travel upon the tracks 35 and thus carry and support the forward end of the carriage. A pair of similar rollers 43 are mounted on the rod 39 adjacent to the inside face of the lugs 38 and are held in spaced relation by a sleeve 44 interposed between the rollers. The function of these rollers is to carry the weight of the boom when the dipper is being loaded as shown in Figure 2. A pair of hangers 45 similar to the ones provided at the forward end of the carriage are pivotally connected by the pin 46 to the rear ends of the side bars 36 of the carriage and in like manner are arranged to travel upon the tracks 35 to carry the rear end of the carriage. A rod 47 is secured to the hangers 45 and has mounted thereon a pair of arms 48 depending therefrom and slidably connected to the rear end of the dipper 49 by suitable guides 51 secured thereto. A cross-bar 52 is pivotally mounted in bearings 53 provided on the arms 48 and has a cable 54 connected thereto by means of a suitable clevis 55. This cable passes over a sheave 56 rotatably mounted in the rearmost end of the boom, thence upwardly over a similar sheave 57 mounted near the uppermost end of the mast and forwardly to the loading and lifting drum 14. A pair of rollers and a spacing sleeve are mounted on the rod 47 between the arms 48 and have the same function as the rollers and sleeve mounted on the rod 39 on the forward hangers, and therefore, will be designated by like numerals.

A pair of supporting arms 58 are pivotally connected by the pins 59 to the rear ends of the bar 36 adjacent the pins 46 and have their forward ends connected to the dipper by links 61. A transverse bar 62, preferably round in cross-section, is secured at each end to the arms 58 and is arranged to engage a pair of dogs 63 mounted on a shaft 64 pivotally mounted in suitable bearings, provided in the bars 36, as shown in Figures 2 and 3. This bar also functions as a tie-rod between the supporting arms 58. The dogs 63 have upwardly extending ends 65 arranged to engage a pair of adjustably mounted stops 66 secured by suitable means to the diagonal braces 34 of the boom 29. Coiled springs 67 yieldingly hold the dogs in their normal position against a stop lug 68 secured to the bars 36 as shown in Figure 3. A bail 69 is connected to the forward end of the dipper by suitable means such as plates 71 riveted to the side walls of the dipper. These plates may be provided with a plurality of apertures 72 for the up and down adjustment of the bail with re-

spect to the lower cutting edge of the dipper to increase or decrease the tendency of the dipper to dig into the soil when being loaded. A cable 73 is connected to the bail and extends upwardly over a sheave 74 rotatably mounted on the pivot 19 supporting the base of the mast, thence forwardly to the loading drum 13.

When it is desired to lower the dipper from its unloading position, shown by dotted lines in Figure 1 and full lines in Figure 4, into the ditch or trench for loading, the lifting and unloading drum 14 is released or reversed thereby unwinding the cable 54 until the dipper engages the bottom of the ditch as shown by full lines in Figure 1. The loading drum 13 is then started and as the cable 73 is wound about the drum the dipper commences to move forwardly and upwardly as shown in Figure 2. When the dipper is in the above position the dogs 63 are in engagement with the transverse bar 62 and as the loaded dipper is elevated out of the ditch by means of the cable 54 for depositing the excavated material on either side of the trench, the forward end of the dipper is suspended on the dogs 63 and the rear end on the arms 48, as shown in Figure 3. Also as the loaded dipper is raised the rear end of same is lowered to the position shown in the above figure, the guides 51 sliding downwardly on the arms 48 until they engage stops provided on the arms. I prefer to use the bearings 53 on the arms 48 as stops to arrest further downward movements of the rear end of the dipper with respect to the carriage. By this means of supporting the dipper when loaded, I reduce to a minimum the possibility of the excavated material dropping out of the forward end of the dipper while it is being elevated for unloading. To elevate the boom and dipper out of the ditch the lifting drum 14 is started and as the loading drum 13 is prevented from rotating by a brake or other suitable means, not here shown, the boom is elevated to the position shown by dotted lines in Figure 1. The loading drum 13 is then released and as the lifting drum continues to revolve the carriage carrying the dipper moves rearwardly upon the tracks 35 until the upwardly extending ends 65 of the dogs 63 engage the stops 66. The cross bar 62 is then released from the dogs and the dipper drops to the position shown in the above figure, and in Figure 4, depositing the excavated material. A stop 75 is provided near the end of the boom to limit the rearward movement of the carriage. Also stops lugs 76 are provided on the arms 48 to limit the upward movement of the rear end of the dipper on said arms when in the position shown in the above figure and also while being loaded as shown in Figure 2.

I claim as my invention:

1. The combination with a frame, of a mast pivoted thereon for vertical oscillation and adjustment, a boom pivoted on said mast and having a track thereon, a carriage mounted to slide on said track, a dipper having one end pivotally suspended from the carriage and its opposite end having a link connection to a swinging bar separably attached to the carriage, cables connected with said dipper for moving it back and forth on said boom, means for locking said dipper to prevent premature tilting thereof, and means for tripping said locking means to release said dipper at a predetermined point in its movement on said boom.

2. A combination of a frame, of a mast pivoted thereon, and having means for vertical adjustment, a boom pivotally connected at one end with said mast, and having a track on its under side extending longitudinally thereof, a carriage mounted to move back and forth on said track, a dipper pivotally supported in said carriage, a swinging bar suspended from the carriage and having one end provided with a link connection to the front of the dipper, means mounted in said carriage and engaging said dipper for locking it in its loaded position, means connected with said dipper for moving it back and forth on said boom, and a trip device for releasing said dipper at a predetermined point in such movement.

3. The combination with a frame, of a mast mounted at an incline therein, a boom pivoted on said mast near one end thereof, a carriage mounted to slide longitudinally on said boom, roller bearings connected to the carriage and bearing against the under-side of the boom to support the boom in the operation of filling the dipper, a dipper having a pivotal connection at one end with said carriage, a latch mounted on said carriage for locking said dipper in its loaded position, cables connected with said carriage and dipper for moving them back and forth on said boom, and a trip device for said latch.

4. The combination with a boom, having a track thereon, and a carriage comprising side bars having anti-friction bearings on said boom, arms pivotally connected to said bars near one end thereof, a dipper having pivotal connections with the other ends of said arms, arms pivotally connected with said carriage at one end, and having slideable connections with the other end of said dipper, a cable connected with said last named arms for oscillating them on their pivots, and a cable connected with the opposite end of said dipper for moving it and said carriage longitudinally on said boom.

5. The combination with a boom, and a carriage mounted for longitudinal movement thereon, a pair of arms pivotally connected at one end with said carriage, a dipper,

links pivotally connecting the other ends of said arms with one end of said dipper, a second pair of arms pivotally connected at one end with said carriage, and having slideable bearings on the other end of said dipper, a cable connected with said second pair of arms, and a second cable connected with the opposite end of said dipper.

6. The combination with a boom, having a track thereon, of a carriage composed of a pair of side bars arranged in parallel relation, and having bearings on said track for movement thereon, a pair of arms pivotally connected with one end of said bars, a dipper having a pivotal link connection with the opposite ends of said arms, a second pair of arms connected with said carriage, and mounted to slide in guides on said dipper, cables connected with said second pair of arms and with the opposite end of said dipper, and a latch device for normally locking said first pair of arms, and said dipper in parallel relation substantially with said carriage and said boom.

7. The combination with a boom, having a track thereon, of a carriage composed of a pair of side bars arranged in parallel relation, and having bearings on said track for movement thereon, a pair of arms pivotally connected with one end of said bars, a dipper having a pivotal link connection with the opposite ends of said arms, a second pair of arms connected with said carriage, and mounted to slide in guides on said dipper, cables connected with said second pair of arms and with the opposite end of said dipper, a latch device for normally locking said first pair of arms, and said dipper in parallel relation substantially with said carriage and said boom, and means for tripping said latch device at a predetermined point on said boom.

8. The combination with a frame, of a mast pivoted at one end on said frame, and adapted to overhang a ditch or trench, means for raising and lowering said mast, a boom pivoted at one end near the pivoted end of said mast, a carriage mounted to slide on the under side of said boom, an excavating dipper supported by said carriage and having means for locking it in its loaded position adjacent said boom, cables connected with the opposite ends of said dipper for moving it back and forth on said boom for loading and unloading, and stops adjustably mounted on said boom in the path of said latch device for tripping it and releasing said dipper at a predetermined point in its movement.

9. The combination with a boom, having a track thereon, of a carriage mounted to slide on said track, a pair of arms pivoted on said carriage near one end thereof, a dipper having a pivotal connection with said arms, a rod mounted in said carriage, a sec-

ond pair of arms mounted on said rod and depending therefrom, guides mounted on one end of said dipper in which said second pair of arms are slidable, a cable connected with said second pair of arms, a second cable connected with the opposite end of said dipper from said first named cable, a

latch device mounted in said carriage for normally locking said dipper in its raised loaded position, and means for tripping said latch device to release said dipper. 10

In witness whereof, I have hereunto set my hand this 26th day of May, 1922,

CLARENCE E. PARKER.
